UNITED STATES PATENT OFFICE.

WILLIAM C. MEYER, DECEASED, LATE OF BEVERLY, MASSACHUSETTS, BY ANNE WEBSTER MEYER, ADMINISTRATRIX, OF BEVERLY, MASSACHUSETTS, ASSIGNOR TO UNITED SHOE MACHINERY CORPORATION, OF PATERSON, NEW JERSEY, A CORPORATION OF NEW JERSEY.

LIP-TURNING MACHINE.

Application filed September 26, 1924, Serial No. 740,101. Renewed July 5, 1938.

This invention relates to lip-turning machines. As herein illustrated the invention is embodied in a machine for turning back the lips or channel flaps of outsoles for Mc-Kay sewed shoes, although certain features 5 of the invention are capable of embodiment in machines for operating upon other kinds of soles.

In a copending application, Serial No. 10 540,037, filed Feb. 28, 1922, by Arthur J. Langlois and Willis H. Mansfield, there is disclosed a channel lip-turning machine wherein the sole is fed between cooperating 15 rotary members one of which consists of a feeding disk arranged so that its side face will engage that portion of the feather of the sole which is normally covered by the channel lip or flap, and wherein the channel lip or flap is turned by means of a rotary lip-turning wheel which is coaxial with the feeding disk but is mounted for rotation 20 independently thereof.

One object of the present invention is to provide certain improvements in the construction and organization of lip turning machines for the purpose of rendering them more efficient and reliable in operation.

To the accomplishment of this object, one feature of the invention consists in the combination, in a machine of the class described, 30 of work-feeding devices arranged to operate upon opposite sides of the work, and having work-engaging surfaces constructed and arranged to afford only restricted areas of contact with flat portions of the work, and a carrier for one of said devices mounted for tilting adjustment about an axis located at a point remote from the work but substantially 35 in the plane of the work (i. e., in the plane or path of that portion of the work which is being operated upon by the work feeding devices), and extending in the direction of work feed. As illustrated, the work feeding members have convex or bulging peripheries 40 adapted to afford only restricted areas of contact with flat portions of the sole margins, and the feeding members are further so constructed and arranged that by mounting the carrier for the tiltable member in 45 the above-described manner the areas of contact of the members with the opposite sides of the work will bear substantially the same 50 relation to each other transversely of the

sole margin, and the action of the work under the influence of the feed members will be 55 the same, irrespective of variations in the thickness of the work. Furthermore, the illustrated work-feeding member is rendered extremely sensitive to variations in the thickness of the work and is capable of moving toward or from the cooperating feed member so as to adjust itself freely to avoid the possibility of unduly compressing the sole margin and thereby injuring or defacing it in any way or interfering with the manual guiding 60 of the work.

In accordance with a further feature of the invention the illustrated machine comprises a pivotally mounted carrier in which is journaled a shaft carrying a lower feed 70 roll, a driven pulley carried by said shaft, a driving pulley, and a belt connecting said pulleys, the driven pulley being so located, relatively to the pivotal axis of the carrier, that the distance between the pulleys will remain substantially constant irrespective of changes in the tilting adjustment of the carrier. 75

Another object of the invention is to provide means for opening the channel and 80 raising the lip into position to be acted upon by the lip-turning wheel, so constructed and arranged that it will be capable of following the curves or bends in the channel of a molded sole without danger of leaving the 85 channel or unduly distorting the channel lip.

With this object in view, the illustrated machine is provided with a channel opening device or plow which is mounted for tilting 90 adjustment about an axis transverse to the direction of work feed and substantially parallel to the plane of the work. As shown the plow is not only capable of tilting adjustment as above described but is also capable of adjustment in the direction of its pivotal axis in accordance with the width 95 of the channel in the sole to be operated upon.

The invention further consists in improvements in the mounting of the upper feed member and the lip-turning member, in improved means for driving said members, and in various details of construction and arrangements of parts hereinafter described 100 and claimed.

The invention will best be understood by reference to the following description of the preferred embodiment thereof illustrated in the accompanying drawings, in which:

5 Fig. 1 is a view, partially in side elevation and partially in section, of a machine constructed in accordance with the present invention;

10 Fig. 2 is a detail view, partially in plan and partially in section, on the line 2—2 of Fig. 1, showing particularly the relation of the operating instrumentalities to the work;

15 Fig. 3 is a perspective view illustrating the operation of the lip-turning wheel, the lip-raising plow and the presser foot;

20 Fig. 4 is a detail sectional view through the operating instrumentalities of the machine illustrating their operation upon the work;

25 Fig. 5 is a view, partially in front elevation and partially in section of the machine, the section being taken on the line 5—5 of Fig. 1; and

Fig. 6 is a rear elevational view of the machine.

Referring to the drawings, the operating instrumentalities comprise a lower feed roll 10, an upper feed member or disk 12 and a lip-turning member or wheel 14. While these instrumentalities operate to feed the work and turn back the channel lip in substantially the same manner as corresponding devices in the copending application above referred to, various improvements relating to the construction, mounting and driving thereof have been embodied in the illustrated machine, as will now be described. The work-feeding and lip-turning devices above mentioned are supported by a frame 16 which is made in the form of a housing shaped to enclose the driving mechanism and adapted to be mounted upon a work bench or other support. Journaled within bearings 18 and 20 formed within the upper portion of the frame or housing 16 is a horizontal main shaft 22. As shown in Fig. 1, a longitudinal tongue-and-groove driving connection 24 is provided between the main shaft 22 and a driving shaft 26 which is coaxial with the main shaft 22 and is journaled at its inner end within the bearing 20 and at its outer end in a bearing formed in a bracket 28 detachably secured to the rear of the frame 16. The driving shaft 26 carries a pulley 30 adapted to be connected by a belt 32 with any suitable source of power. The tongue-and-groove connection 24 enables the shaft 26 readily to be disconnected from the shaft 22 by removing the bracket 28, and the shaft 26 and the bracket 28 may be replaced by an electric motor having a motor shaft provided at one end with a tongue adapted to enter the groove in the main shaft 22 to establish driving connection with the motor.

The main shaft 22 is directly connected to drive the lip-turning wheel 14 through intermeshing worm gears 34 and 36, the gear 34 being secured to the shaft 22 and the gear 36 being secured to the upper section 38 of a two-part hollow shaft or sleeve, the lower section 40 of which carries the lip-turning wheel. The upper feed disk 12 is carried at the lower extremity of a shaft 42 which extends upwardly through the hollow shaft 70 comprising the sections 38 and 40 and has secured to its upper portion a belt pulley 44. The lower feed roll 10 is carried by a shaft 46 which is journaled in a pivotally mounted carrier 48 and has secured thereto the belt 75 pulley 50. The lower feed roll 10 and the upper feed disk 12 are driven at substantially the same radial speed by means of a single belt 52 which passes over both the pulleys 44 and 50, and over an idle pulley 54 and a driving pulley 56. The driving pulley 56 is secured to a horizontal pulley shaft 58 which is connected with the main shaft 22 by means of intermeshing worm gearing 60. The idle pulley 54 is carried by a bracket 62 pivoted at 64 to the frame 16 so that it may be adjusted to take up the slack in the belt 52. The bracket 62 is secured in adjusted position by means of a bolt 65 which extends through an arcuate 95 slot in the bracket.

The lower feed roll 10 is of the shape of a conoidal frustum having convex or bulging sides (see Fig. 4) and comprises an annular member 66 which encircles the shaft 46 and is clamped between a collar 67 fast on said shaft and a nut 68 which is threaded upon the outer end of the shaft. The annular member 66 is so located that its periphery engages the lower side of the work at a point opposite the point of engagement of the upper feed disk with the work and the periphery of the member 66 is roughened or knurled to increase its tractive effect upon the work without causing it to mar the work. The carrier 48 for the feed roll 10 comprises a bearing portion, in which the shaft 46 is journaled, and a yoke portion 70 the arms of which carry trunnions 72 which are mounted to turn in bearings in the side walls of the frame 16, thus providing for free up and down tilting adjustment of the lower feed roll 10. The axis of the trunnions 72 is located substantially in the plane or path of the work, or that portion of the work which is being operated upon by the feed members and the lip turning wheel, so that the tilting adjustment of the lower feed roll will not effect any substantial change in the illustrated co-operative relation of the restricted areas of contact of the feed members with the work. The carrier 48 extends through an aperture 49 in the front of the frame 16 and is positioned with the shaft 46 inclined as shown in Fig. 1 so that the conoi- 130

dal periphery of the lower feed roll will support flat portions of the work in a substantially horizontal plane. The shaft 46 extends downwardly beyond the bearing portion of the carrier 48 to receive the pulley 50 and is formed with a pair of depending ears 74 between which is pivoted the upper end of a rod 76 the lower end of which is guided for up-and-down movement in a bearing 78. The rod 76 is adapted to be connected with a foot treadle (not shown) by means of which the lower feed roll 10 may be lowered to facilitate the introduction of the work between the feed members. A spring 80 surrounds the rod 76, between the bearing 78 and a collar 82 upon the rod, and urges the feed roll 10 upwardly into yielding engagement with the work. The collar 82 is backed up by nuts 84 which may be turned to vary the tension of the spring 80. Upward movement of the feed roll 10 under the influence of the spring 80 is limited by engagement of an abutment 86 formed on the carrier 48 with a stop screw 88 carried by the frame, while downward movement of the feed roll 10 is limited by means of a stop screw 90 arranged to engage with the ears 74. A lock nut 92 on the stop screw 88 provides means for securing the latter in adjusted position. The axis of tilting adjustment of the lower feed roll extends substantially at right angles to the axis of the driven pulley 50 and is located substantially midway between the positions assumed by the lower stretch of the belt 52 at the opposite limits of adjustment of the lower feed roll. In other words, the axis about which the lower feed roll may be adjusted is located substantially centrally of the field of displacement of the belt 52 resulting from tilting adjustment of the carrier 48 and the lower feed roll. Consequently, such adjustment of the feed roll will not appreciably tighten or loosen the belt. It will be apparent from an examination of Fig. 1 that the lower feed roll is so shaped and the axis of the lower feed roll carrier is so located that said roll will engage the work throughout an area of substantially the same extent and location relatively to the sole edge and relatively to the point of contact of the upper feed disk with the work irrespective of up or down movement of said roll due to variations in the thickness of the sole being operated upon. Thus the action of the work under the influence of the feed members will be the same irrespective of variations in the thickness of the work. By making the lower feed roll in the form shown, this roll is particularly adapted for feeding those portions of a sole margin which are flat, since a restricted area of feeding contact is obtained which has been found to be sufficient to insure positive feeding of the sole without interfering with the manual guiding or swing-

ing of the sole as the lip-turning operation progresses around the margin thereof. Further, the bulging of the periphery of the lower feed roll enables the roll to conform substantially to the transverse curvature along the shank portions of a molded sole so as to avoid flattening out this part of the sole. On account of the small diameter of the lower feed roll the roll will pass over the abrupt bend at the junction of the shank and forepart of a molded sole of the cottage shank type without flattening out the bend and the roll has no tendency to distort or break down the molded contour of any part of a molded sole.

As best shown in Fig. 4, the upper feed disk 12 has a slightly bulging lower face adapted to engage the upper side of the feather of the sole at a point directly above the annular member 66 of the lower feed roll. The upper portion of the upper feed disk 12 is of truncated conical form and is normally contained within a similarly shaped recess in the lip-turning wheel 14. The feed disk 12 is provided with a smooth periphery adapted to engage the base of the turned channel lip to assist in guiding the sole. The feed disk is threadedly connected with the reduced lower extremity of the shaft 42.

The shaft 42 carrying the upper feed disk 12 is journaled at its upper end within a bearing 96 formed within a housing member 98 detachably secured to the front of the frame 16, while the lower portion of the shaft 42 is journaled within the sections 38 and 40 of the sleeve which carries the lip-turning wheel. The pulley 44, carried by the shaft 42, is located between upper and lower ball thrust bearings 100 and 101, which prevent endwise displacement of the shaft. The lip-turning wheel 14 is shaped as shown in Figs. 2, 3 and 4, and is provided with four equally spaced apart projecting arms each having upon its under side an upwardly and outwardly curved work-engaging surface adapted to wipe across the inner face of the channel lip as the wheel 14 rotates, so as to turn the lip backward and lay it down against the upper face of the sole. A central conical recess or socket 91 is formed in the lower side of the lip-turning wheel to receive the upper feed disk 12.

The lower section 40 of the lip-turning wheel shaft is journaled in a suitable bushing 102 which is threaded at its lower end within a bearing 104 formed in the lower portion of the housing 98. The lip-turning wheel shaft is supported in the bearing 104 by means of an annular flange 106 which is formed at the upper extremity of the lower shaft section 40 and rests upon a ball bearing 108 which is interposed between the bearing 104 and the flange 106. The upper section 38 of the lip-turning wheel shaft is

mounted to turn freely upon the shaft 42 and inasmuch as the gear 36 is fast upon this shaft section, the latter is prevented from being axially displaced by engagement 5 of the gear 36 with the bearing 101 and with the gear 34. The upper and lower sections of the lip-turning wheel shaft are coupled together to turn in unison by means which permits the lower shaft section to move longitudinally relatively to the upper shaft section so that the lip-turning wheel may yield relatively to the upper feed disk in accordance with variations in the thickness of the portion of the lip which is being engaged by the lip-turning wheel. This coupling means comprises two tongues 110 which depend from the upper shaft section at diametrically opposite points and are slidably received in similarly disposed peripheral notches in the flange 106. A spring 112 encircles a hub 114 depending from the gear 36, the spring bearing at its upper end against said gear and at its lower end against the flange 106. The force of the spring 112 tends to hold the lip-turning wheel yieldingly in a lower position determined by engagement of the flange 106 with the bearing 108, but permits the lip-turning wheel to yield upwardly relatively to the upper feed disk as may be necessary to accommodate variations in the thickness of the lip. To hold the upper ball race of the bearing 108 in ball-retaining position as the lip-turning wheel and the flange 106 yield upwardly, a spring 116 is seated in a socket of the flange 106 and arranged to press downwardly upon the upper ball race of said bearing. The lowermost position of the lip-turning roll 14 is determined by engagement of the ball bearing 108 with the upper end of the bushing 102. The lower end of the bushing 102 projects below the bearing 104 and is notched as shown at 103 to receive a suitable tool by which it may be turned to raise or lower it in the bearing 104 and thus to vary the lower position of the lip-turning wheel. A lock nut 105 is provided to secure the bushing 102 in adjusted position.

On account of the slight transverse bulge in the periphery of the lower feed roll 10 and the convex or rounded contour of the lower face of the upper feed disk 12 these members are enabled to embed themselves 55 to a very slight extent in the sole material as they are yieldingly pressed into feeding engagement therewith and thus they are caused to grip the sole so as to resist edge-wise movement of the sole away from the edge gage. It is desirable that the sole shall be continuously urged toward the edge gage while it is being fed so as to render it unnecessary for the operator to exert constant pressure against the sole while it is being operated upon. To this end the lower feed

roll is pivotally mounted, as above described, in such a manner that it will move upwardly and rearwardly under the force of the spring 80 and will thus exert an influence tending to cause the sole to hug the edge gage. Furthermore, the larger end of the lower feed roll is arranged to engage the sole at a point nearer the sole edge than the smaller end of said feed roll and as a result the roll will tend to swing the sole toward the edge gage 75 on account of the greater lineal speed of the feeding surface at the larger end of the feed roll. The tendency of the sole to hug the edge gage is further facilitated by the mounting of the upper feed disk with its 80 axis inclined to the horizontal at the angle shown in the drawings. The inclination of the axis of the upper feed disk and the similar inclination of the axis of the lip-turning wheel enables the operator more easily to 85 watch the progress of the lip-turning operation.

To locate the channel lip transversely relatively to the lip-turning wheel, an edge gage 120 is provided. The edge gage 120 is 90 in the form of a roller which is pivotally mounted upon a carrier 122 having a horizontal shank 124 which is received in a socket formed in a bracket or cross-bar 126 which bridges the aperture 49 and is removably secured to the frame. The shank 124 of the edge gage carrier extends horizontally at right angles to the direction of feed and is rigidly secured within its socket by means of a clamp screw 128 which may be 100 loosened to permit adjustment of the edge gage in accordance with the width of the feather and the lip of the sole.

Before the lip is acted upon by the lip-turning wheel, a preliminary channel-opening or lip-raising operation is performed by means of a plow 130, best shown in Fig. 3, which is located forwardly of the lip-turning wheel and is arranged to enter the channel and to raise the lip to a position just above the plane of the lip-turning wheel so that the lip may be properly engaged and acted upon by the wheel.

The plow 130 is formed with a pointed tip shaped to enter the channel and raise the lip as the sole is fed. The plow is mounted for free lateral tilting movement about an axis perpendicular to the direction of feed of the sole and in addition the plow is adjustable transversely of the direction of work feed in accordance with the width of the channel in the particular run of soles being operated upon. To this end the plow is fixedly secured to the outer extremity of a trunnion 132 which is mounted with provision for axial adjustment in ball bearings carried by the bracket 126. As shown the ball bearings comprise inner ball races 134 and 136 rigidly secured to the trunnion 132 and outer ball races 138 and 140 which are

slidable axially within a cylindrical bore 142 in the bracket 126. The bracket 126 is split as shown at 144 in such a way that it may be contracted to clamp the outer ball race 138 to secure the plow in adjusted position transversely with respect to the channel. A binding screw 146 is provided for contracting the bracket 126 so as to clamp the ball race 138. The plow is curved as shown in Fig. 3 to avoid interference with the lip-turning wheel 14 and the point of the plow while located as close to the lip-turning wheel as practicable is nevertheless offset forwardly from the axis of the trunnion 132 about which the plow is free to tilt. Consequently as the plow tilts in following the up or down curves in the channel of a molded sole the point of the plow will be raised or lowered as the case may be to insure that it will remain within the channel.

Immediately after being acted upon by the lip-turning roll, the backwardly turned lip passes beneath a guide finger 150 which assists in setting the lip and prevents the sole from being tilted by the operator so as to cause any portion of the sole to be injured by the rapidly rotating lip-turning wheel. The guide finger 150, as best shown in Fig. 3, is arranged to project transversely across the channel lip and is provided with a cylindrical shank portion 152 which is rigidly secured in a socket in the bracket 126 by means of a clamp screw 154. The screw 154 may be loosened to permit adjustment of the guide finger transversely with respect to the direction of work feed.

Inasmuch as the edge gage, the plow 130 and the guide finger 150 are all mounted upon the removable bracket 126, they may be conveniently assembled before the bracket is secured in place, and the bracket may be removed at any time to render the parts mounted thereon more conveniently accessible for adjustment.

The machine, as herein described, is of simple and rugged construction. The mechanism of the machine is compactly arranged and, with the exception of the instrumentalities which engage the work, is enclosed within in a casing which protects the mechanism from injury and from accumulations of lint and dust. Furthermore, the construction and arrangement of the driving mechanism is such that the machine is capable of operating at high speed substantially without objectionable vibration and noise.

Having described the invention, what is claimed as new and desired to be secured by Letters Patent of the United States is:

1. In a machine of the class described, work-feeding devices arranged to operate on opposite sides of the work, each having work-engaging surfaces constructed and arranged to afford only restricted areas of con-

tact with flat portions of the work, and a carrier for one of said devices mounted for tilting adjustment about an axis located at a point remote from the work but substantially in the plane of the work and extending in the direction of work feed to accommodate pieces of work of different thicknesses.

2. In a machine of the class described, a work-feeding member arranged to have a restricted area of contact with the upper side of a piece of work, and a work-supporting feed roll arranged to have a restricted area of contact with the lower side of the work in a predetermined relation to the area of contact of said member with the work and to co-operate with said feeding member in feeding the work, said feed roll being mounted for up-and-down adjustment about an axis spaced from the path of the work, but located substantially in the plane of the work to accommodate work of different thicknesses without varying said relation of said areas of contact with the work.

3. In a machine of the class described, a work-feeding member arranged to have a restricted area of contact with the upper side of a piece of work, a work-supporting feed roll arranged to have a restricted area of contact with the lower side of the work in a predetermined relation to the area of contact of said member with the work and to co-operate with said feeding member in feeding the work, said feed roll being mounted for up-and-down adjustment about an axis removed from the path of the work but located substantially in the plane of the work to accommodate work of different thicknesses without varying said relation of said areas of contact with the work, and means for limiting the movement of said feed roll in both directions.

4. In a machine of the class described, work-feeding devices arranged to operate on opposite sides of the work, each having work-engaging surfaces constructed and arranged to afford only restricted areas of contact with flat portions of the work, a carrier for one of said devices mounted for swinging adjustment about an axis located substantially in the plane of work feed to accommodate pieces of work of different thicknesses, yielding means for maintaining said devices in cooperative engagement with the work, and operator-controlled means for separating said devices.

5. In a machine of the class described, an upper work-feeding member arranged to have a restricted area of contact with the upper side of a sole, a lower feed roll arranged with its axis inclined with respect to the plane of the sole and having a periphery shaped to provide for a restricted area of feeding engagement with the sole in a predetermined relation to the area of contact

of the upper feed member with the sole, and a carrier for said roll pivoted for tilting adjustment about an axis arranged relatively to the plane of the work to insure engagement between the roll and the sole throughout an area bearing substantially the same relation to the area of engagement of the upper feed member with the sole irrespective of changes in the relation of the feed members due to variations in the thickness of the work.

6. In a machine of the class described, a shaft carrying a feed roll and a driven pulley, a feed member for cooperating with said roll to feed the work, a driving pulley, a belt connecting said pulleys, and a bearing for said shaft mounted for tilting adjustment about an axis arranged to enable said feed roll to move toward and from said feed member while maintaining substantially constant the distance between said pulleys.

7. In a machine of the class described, a shaft carrying a feed roll and a driven pulley, a member for cooperating with said roll to feed the work, a driving pulley, a belt connecting said pulleys, and a bearing for said shaft mounted for adjustment about a pivotal axis located substantially centrally of the field of displacement of the belt resulting from adjustment of said bearing.

8. In a machine of the class described, a work supporting feed roll, feeding means cooperating with said roll and arranged to engage the opposite side of the work, a driving pulley connected with said roll, a belt arranged to drive the pulley, and a carrier for the roll and pulley mounted for up-and-down swinging adjustment about an axis located substantially in the plane of work feed and substantially midway between positions of the belt at opposite limits of adjustment of said carrier.

9. In a machine of the class described, work-feeding devices, a feed roll arranged to cooperate with said devices to feed the work in a substantially horizontal plane, said roll being rotatable about an axis inclined to the horizontal, a driving pulley connected with said roll, a belt for said pulley, and a carrier for said roll and pulley mounted to tilt freely about a horizontal axis located substantially in the plane of work feed and substantially midway between positions of the belt at opposite limits of adjustment of said carrier.

10. In a machine of the class described, cooperating rotary work-feeding devices having convex faces arranged to engage opposite sides of the work, two shafts one for each of said devices, one of said shafts being inclined upwardly and inwardly and the other downwardly and outwardly from a sole being operated upon by the machine, two driven pulleys connected one with each of said

shafts, and a single belt arranged to drive both of said pulleys.

11. In a machine of the class described, cooperating rotary work-feeding devices having bulging faces arranged to engage opposite sides of the work, two driving pulleys connected one with each of said devices, a carrier for one of said devices mounted to permit relative movement of said devices toward and from each other in directions substantially at right angles to the axis of one of the devices to accommodate work of different thicknesses, and a single belt passing over both of said pulleys for driving both of said devices.

12. In a machine of the class described, cooperating rotary work-feeding devices arranged to engage opposite sides of the work, two driving pulleys connected one with each of said devices, a single belt arranged to drive both of said pulleys, and a carrier for one of said devices mounted to permit relative movement of said devices toward and from each other without correspondingly varying the distance between said pulleys.

13. In a machine of the class described, a lower feed roll having a convex conoidal surface, a shaft for said roll inclined to the horizontal to enable said surface to engage the lower side of a sole disposed in a substantially horizontal plane, an upper shaft inclined to the perpendicular but arranged in the same plane as the lower shaft, a feed member on the upper shaft cooperating with the feed roll to feed the sole, a pulley on each of said shafts, a driving shaft extending transversely of the common plane of said shafts, a pulley on the driving shaft, and a single belt passing over all of said pulleys for driving the feed roll and said feed member.

14. In a machine of the class described, two cooperating rotary feed members having convexly rounded work-engaging faces and having their axes inclined relatively to each other, one upwardly and outwardly and the other downwardly and inwardly relatively to a piece of work being fed between them, a yielding mounting for one of said members enabling said members to move toward and from each other, driven pulleys connected one with each of said members, and a single belt for driving said pulleys.

15. In a machine of the class described, cooperating feed members having convex faces for engaging opposite margins of a sole, a shaft for one of said feed members inclined upwardly and inwardly with respect to that portion of the margin of a sole which is engaged by said member, a shaft for the other of said members inclined downwardly and outwardly with respect to that portion of the margin of the sole engaged by said other member, driven pulleys one on each of said shafts, a driving pulley, an

idle pulley, and a belt passing over all of said pulleys for driving both of said feed members.

16. In a machine of the class described, 5 the combination with work-feeding devices arranged to operate on opposite sides of the work, a shaft carrying one of said devices, a carrier for said shaft pivotally mounted for free tilting movement transversely of 10 the direction of the work feed, a driven pulley on said shaft, a driving pulley, and a belt connecting said pulleys, the driven pulley being located relatively to the pivotal axis of the carrier so that the distance 15 between said pulleys will remain substantially constant irrespective of changes in the tilting of the carrier.

17. In a machine of the class described, 20 cooperating rotary feed members for engaging opposite sides of the feather of a channeled sole, a plow operating in advance of the feeding means for entering the channel preliminarily to raise the channel lip, said plow having a trunnion extending therefrom, and a bearing for said trunnion constructed and arranged to enable the plow to tilt freely about an axis substantially parallel to the plane of the sole.

18. In a machine of the class described, 25 cooperating rotary feed members for engaging opposite sides of the feather of a channeled sole, and a plow operating in advance of the feeding means for entering the channel preliminarily to raise the channel lip, said plow being mounted for tilting adjustment about an axis transverse to the direction of work feed but substantially parallel to the plane of the sole to enable the plow to follow the channel of a molded sole as 30 portions of the sole margin angularly disposed relatively to the plane of the forepart approach the feeding means.

19. In a machine of the class described, 35 means for feeding a channeled sole and for turning back the channel lip as the sole is fed, and a plow operating in advance of the feeding means for entering the channel preliminarily to raise the channel lip, said plow being mounted to tilt freely about an axis 40 transverse to the direction of work feed but substantially parallel to the plane of the sole and having its lip-engaging portion offset from its axis of tilting movement.

20. In a machine of the class described, 45 means for feeding a channeled sole and for turning back the channel lip as the sole is fed, and a plow operating in advance of the feeding means for entering the channel preliminarily to raise the channel lip, said plow being mounted with provision for tilting adjustment about an axis substantially 50 parallel to the plane of the sole and transverse to the direction of work feed and also for adjustment in the direction of said axis.

21. In a machine of the class described,

means for feeding a channeled sole and for turning back the channel lip as the sole is fed, and a plow operating in advance of the feeding means for entering the channel preliminarily to raise the channel lip, said 70 plow having a trunnion substantially parallel to the plane of the sole and extending at right angles to the direction of work feed, a ball bearing for said trunnion enabling the plow to tilt freely about the axis of the trunnion, the bearing and said trunnion being adjustable in unison in the direction of said axis to vary the transverse relation of the plow to the channel, and means for securing the plow in its transversely adjusted position. 80

22. In a machine of the class described, work-feeding and lip-turning means, a plow for preliminarily opening the channel of a sole, a trunnion on said plow extending at 85 right angles to the direction of work feed, a fixed bracket having a recess for receiving said trunnion, the wall of said recess being split lengthwise of the trunnion, an anti-friction bearing within said recess comprising an inner ball race secured to said trunnion and an outer ball race mounted for sliding adjustment axially of the trunnion to enable the plow to be adjusted transversely of the channel lip, and means for contracting the wall of said recess to clamp the outer ball race to secure the plow in transversely adjusted position. 90

23. In a machine of the class described, means for supporting and feeding the work, 100 a driving shaft composed of two parts arranged in coaxial end-to-end relation, means constructed and arranged detachably to couple said shaft parts together for rotation in unison while permitting lengthwise relative 105 movement thereof, a rotary lip-turning member carried by one of said shaft parts, means for driving the other shaft part, and a spring for exerting pressure against one of said shaft parts to hold said member 110 yieldingly in engagement with the work.

24. In a machine of the class described, 115 means for supporting and feeding the work, a member rotatable about an axis intersecting the plane of the work and having a convex face for turning the channel lip toward the face of the work, yielding means for pressing said member toward the work-supporting means, and means for limiting the extent of movement of said member under 120 the influence of said yielding means.

25. In a machine of the class described, 125 means for supporting and feeding the work, a rotary lip-turning member arranged with its axis intersecting the plane of the work at the outer side of the lip, a shaft carrying said member yieldable axially to enable the member to accommodate itself to lips of different thicknesses, a fixed bearing for said shaft, a flange on the shaft at one end of 130

the bearing, and a bushing threaded within said bearing and engaging said flange for adjustably limiting the movement of the lip-turning member toward the work-supporting means.

26. In a machine of the class described, a frame, work-feeding and lip-turning means carried thereby, a bracket detachably se-

cured to the frame, an edge gage, a channel-opening device, and a work guide carried by 10 said bracket.

In testimony whereof, I have signed my name to this specification.

ANNE WEBSTER MEYER,
Administratrix of the Estate of William C.
Meyer, deceased.
